LOOSE-LEAF BINDER AND LATCHING
MECHANISM

Charles V. St. Louis, Benton Harbor, Mich., assignor to Remington Rand Inc., New York, N. Y., a corporation of Delaware

Application January 21, 1948, Serial No. 3,593

6 Claims. (Cl. 129—1)

1

This invention relates to improvements in loose leaf binders and particularly to a structure wherein the sheet binding unit may be mounted for movement relative to the covers and back member.

The invention comprehends use of latch means on a sheet binding unit and an attaching bar detachably mounted on a back and cover structure for a binder in which the latch means will secure the sheet binding unit against relative hinging movement to the back member on the attaching bar. This secures the sheet binding unit to the back member so that it can be used in the usual manner in which a loose leaf binder is employed for reference to the records contained on the sheets bound between a pair of binder bars and also for closing of the covers against opposite sides of the bound sheets when the binder is not in use so it may be transported from place to place. These features of construction facilitate the use of information carried in the loose leaf binder on the sheets bound in the sheet binding unit, as well as in pockets carried by the covers because the sheet binding unit has the latch means released to allow relative movement of the binding unit to the back and covers so it can lie flat on a desk or table over one cover for reference to the information carried on the sheets between the binder bars while at the same time providing more convenient reference to information contained in pockets carried by one of the covers. This enables special data used in giving information on insurance rates of various kinds as well as in connection with the presentation of data used in sales, engineering and other types of business to be more conveniently arranged and referred to.

In the drawings:

Fig. 1 is a plan view of the binder with the covers shown in open position and the sheet binding unit released and shown in angular position to the back member.

Fig. 2 is a front elevation of the sheet binding unit detached from the back member with portions broken away and shown in cross-section.

Fig. 3 is a horizontal cross-section taken on line 3—3 of Fig. 2.

Fig. 4 is a vertical cross-section taken on line 4—4 of Fig. 1 showing the sheet binding unit in angular relation to the back member.

Fig. 5 is a vertical cross-section similar to Fig. 4 showing the sheet binding unit latched to the back member against hinging movement.

Fig. 6 is a vertical transverse cross-section taken on line 6—6 of Fig. 1.

Fig. 7 is an end elevation of the binder showing the sheet binding unit latched to the back member as shown in Fig. 5.

The binder has covers 1 and back member 2

2

formed of suitable material, such as leather or the like. Covers 1 are adapted for hinging movement on opposite sides of back member 2 as indicated at 3. The edges of covers 1 are provided with suitable flaps adapted to carry portions of a zipper fastener so that the zipper may be used to secure the covers together and fully enclose the sheet body when the case is being carried about. Handles 4 are mounted on the outer free edges of each cover for use in carrying the binder.

Mounting bar 5 is secured to back member 2 by means of an inner back cover 6 stitched about its margins to back member 2 and also stitched along opposite sides of mounting bar 5, so that the mounting bar is rigidly secured to back member 2. Mounting bar 5 is therefore engaged between inner back cover strip 6 and back member 2, as shown in Figs. 6 and 7. A pair of attaching posts 7 are riveted on mounting bar 5 in spaced parallel laterally extending relation. Posts 7 project through inner back cover 6 as shown in Fig. 4, and have the free ends provided with an annular groove 8.

Sheet binding unit is generally indicated at 9 for binding a plurality of loose sheets along one margin. The sheet binding unit illustrated has a pair of binder bars 10 and 11 adapted to engage opposite sides of a sheet body. Binder bar 11 forms a bottom binder bar while bar 10 forms a top binder bar. A flexible binding 12 of suitable material is secured to bars 10 and 11 and mounts them for relative movement toward and from each other in substantially spaced parallel relation. Flexible binding 12 provides for varying the capacity of the binder between desired limits and is shown in the drawings with bars 10 and 11 spaced apart to carry the maximum size of sheet body with flexible binding 12 taut. As illustrated, flexible binding 12 embraces bars 10 and 11 and is stitched or otherwise secured together at suitable positions along the edges of the bars to hold the layers of the flexible binding material in superposed relation together to effectively support bars 10 and 11.

Bottom bar 11 carries a plurality of sheet engaging posts 13 and 14 respectively, each rigidly secured to bar 11. These posts are each of tubular form so as to telescopically receive binder posts 15 and 16 respectively. Posts 15 are riveted to transfer bar 17 in aligned relation with posts 13 so that posts 15 will telescope into tubular posts 13 in the manner clearly illustrated in Fig. 2. Binder posts 16 are threaded throughout their length and have threaded engagement in the reduced ends of tubular posts 14 so that the length of binder posts 16 projecting beyond the ends of tubular posts 14 may be manually varied by turning the posts to thread them into and out of posts 14. The free ends of binder

posts 16 are provided with grooved heads 18. Transfer bar 17 is provided with apertures 19 in aligned relation with posts 16 for receiving posts 16 in projecting relation through the apertures. Transfer bar 17 may therefore be slidably moved on posts 16 in sheet transferring operations. Transfer bar 17 may be disengaged from posts 16 by movement outwardly off the ends of posts 16 for transferring sheets on posts 15 of the transfer bar in the usual manner employed in post-type binders, well known in the art, in removing, transferring and replacing sheets in the binder.

Top binder bar 10 is transversely slotted in alignment with posts 16, as indicated at 20, for receiving heads 18 of posts 16. Latch bar 21 is engaged with the outer side of top binder bar 10 and secured thereto for a limited sliding movement. Slots 22 at opposite ends of latch bar 21 slidably engage rivets 23 extending therethrough. Rivets 23 are rigidly secured to end portions of binder bar 10. Opposite slots 20 in binder bar 10, latch bar 21 is formed with keyhole slots 24 opening through one side of latch bar 21 at the same side that slots 20 open through bar 10. This provides open slots to receive grooved heads 18 on posts 16 so that the reduced portion of heads 18 providing the grooves will engage in transverse slots 20 and slots 24 with the portions of larger diameter of heads 18 on opposite sides of bar 10 and latch 21. By sliding latch bar 21 to offset the open portion of the slots therein relative to transverse slots 20, latch bar 21 will effectively latch binder posts 16 on top binder bar 10 to hold the sheet body in bound relation against removal of sheets. Transfer bar 17 is applied to posts 16 before top binder bar 10 and normally lies adjacent bar 10 in the bound relation of the sheets in the binder.

Flexible binding 12 has an extension from bottom binder bar 11 which embraces and hingedly mounts attaching bar 25 on the lower rear portion of sheet binding unit 9 as clearly shown in Fig. 6. Attaching bar 25 is provided with apertures aligned with attaching posts 7 so that it may readily engaged and disengaged with over posts 7 in attaching the sheet binding unit to back member 2. A latch bar 26 constructed in a similar manner to latch bar 21 has slots 27 in opposite ends to receive rivets 28 rigidly secured to attaching bar 25 for mounting latch bar 26 on one side thereof for limited sliding movement. Latch bar 26 is formed with keyhole slots 29 in alignment with the post receiving apertures formed in attaching bar 25 so that posts 7 may be projected through the apertures in attaching bar 25 and the enlarged end of slots 29 in latch bar 26. Then, after attaching bar 25 is engaged on posts 7 as shown in Fig. 1, slideable movement of latch bar 26 to the opposite limit will move the portions of keyhole slots 29 of smaller dimension into the grooved ends on posts 7 and effectively latch attaching bar 26 to posts 7 for firmly attaching sheet binding unit 9 to back member 2.

In operation of the binder it will be understood that the user may remove and insert sheets between binder bars 10 and 11 by removing binder bar 10 through releasing latch bar 21 from post 16 and then manipulating the sheets with the use of transfer bar 17. This may be done whether the sheet binding unit 9 is attached to back member 2 or is in detached relation. When sheet binding unit 9 has the desired sheets in bound relation between binder bars 10 and 11, then it may be attached to back member 2 by engaging at-

taching bar 25 and locking it on posts 7 of mounting bar 5. The sheet binding unit is then effectively secured to the covers and back member 2 for convenient manipulation between positions 5 where the bound edge of the sheet body will be in laterally extending relation with respect to back member 2 as shown in Fig. 1, or may be moved into adjacent position against back member 2 as shown in Fig. 7.

10 When the binder is to be closed for carriage or transport, it is usually desired to secure sheet binding unit 9 against relative movement to back member 2 about attaching bar 25. For this purpose a keeper 30 in the form of a sheet metal plate of substantially Z-shape in cross-section is mounted in transverse relation on the inner face of the back member 2 and against the inner face of inner back cover strip 6. One margin of keeper 30 is riveted firmly against the surface of cover strip 6 while the opposite margin is offset as shown in Fig. 5.

A latch plate 31 is formed with slots 32 in aligned relation to receive rivets 33 for mounting latch plate 31 on the central portion of transfer bar 17 for limited sliding movement. The margin of latch plate 31 at the side formed with slots 32 has a handle projection 34. The opposite side of latch plate 31 extends substantially beyond the opposite edge of transfer bar 17 through slot 35 in flexible binding 12 to the rear of the flexible binding where the plate has a recess 36 in one end to provide latch projection 37. Latch projection 37 is in a position to engage under the offset margin of keeper 30 when latch plate 31 is at one limit of its movement on transfer bar 17. At the opposite limit of movement latch plate 31 is disengaged from keeper 30. In this way latch plate 31 and keeper 30 cooperate to secure sheet binding unit 9 adjacent top binder bar 10 to back member 2 when the sheet body is arranged adjacent to back member 2 with the sheets extending in perpendicular relation thereto. This secures the sheet binding unit to binder back member 2 so that it cannot be moved about its flexible hinge connection with attaching bar 25. This position is clearly illustrated in Figs. 5 and 7. It will, therefore, be clear that when latch plate 31 and keeper 30 are interengaged in latching relation that the sheet body is held rigidly against back member 2 so that covers 1 may be moved to a closed position for closing the binder for carrying.

Covers 1 are adapted to have expandible pocket structures 38 mounted on the inner faces thereof for receiving various kinds of data sheets that are not desired for inclusion in the bound sheet body of sheet binding unit 9. In handling technical data of many types such as insurance records, engineering records and the like, it is necessary in sales, management and other types of work using such data to refer to several different sheets at one time. For example, if the sheet binding unit includes a plurality of sheets containing insurance rates while application sheets, instruction sheets, cost figures and so forth are contained on sheets placed in pockets 38, it will be clear that when sheet binding unit 9 is released from back member 2 by disengaging latch plate 31 from keeper 30, sheet binding unit 9 may be moved into the position shown in Fig. 1. The sheets contained in pockets 38 on the inner left-hand cover may be removed from the pockets and laid on the cover for reference purposes while at the same time an operator may refer to the rates 70 carried on the sheets in unit 9. In this way

convenient reference and manipulation of the sheets in unit 9 may be made in connection with the other papers used in connection with the figures carried by the tables in unit 9, in order to supply information to people interested in insurance and the various figures and factors involved in writing insurance policies. Then the sheets may be restored to their respective pockets with sheet binding unit 8 lodged against back member 2 when the binder is ready to be closed and carried about.

The invention claimed is:

1. In a loose leaf binder having a sheet binding unit retaining a sheet body between a pair of binder bars, the combination of a flexible binding attached to said binder bars at opposite edges, an attaching bar, said flexible binding having an extension from one of said binder bars secured to said attaching bar for flexibly connecting said binding unit to said attaching bar for relative movement of a sheet body to said attaching bar, cover members connected by a back member and movable relative thereto into open and closed positions, means on said back member detachably connecting said attaching bar thereto, and latch means having cooperating parts carried by said binder bar unit and back member for detachably securing said sheet binding unit to said back member for holding said unit against movement relative to said attaching bar.

2. In a loose leaf binder having a sheet binding unit for retaining a sheet body therein, the combination of a back member, cover members hinged on opposite sides thereof for movement between open and closed positions relative to said sheet body, an attaching bar, means on said back member detachably connecting said attaching bar to said back member, a flexible strip mounted on said attaching bar and secured to said sheet binding unit for hingedly securing said unit to said attaching bar for movement relative to said back member, and means having complementary interengaging parts on said sheet binding unit and back member for detachably connecting said unit to said back member for retention against relative movement.

3. In a loose leaf binder having a sheet binding unit for retaining a sheet body, the combination of a back member, cover members hinged at opposite sides thereof for movement between open and closed positions relative to said sheet body, an attaching bar, means detachably connecting said attaching bar to said back member, means flexibly connecting said sheet binding unit to said attaching bar for movement relative to said back member, a keeper mounted in transversely extending relation on said back member, and a latch member slidably mounted on said sheet binding unit for cooperative engagement with said keeper to secure said unit to said back member against movement relative thereto.

4. In a loose leaf binder as claimed in claim 3, having the means detachably connecting said attaching bar to said back member comprising posts mounted on said back member for engagement in apertures formed in said attaching bar, and a lock bar slidably mounted on said attaching bar detachably engaging said attaching posts in one position for securing the attaching bar to the back member.

5. A loose leaf binder comprising a back mem-

ber, cover members secured to opposite sides of said back member, a mounting bar secured to said back member having attaching posts, an attaching bar removably engaged on said attaching posts, latch means for detachably locking said attaching bar on said attaching posts and mounting bar, a sheet binding unit having a pair of binder bars to engage opposite sides of a sheet body, a transfer bar detachably associated with said binder bars at one side of a sheet body, cooperating sheet engaging posts mounted on said binder and transfer bars for retaining a sheet body between said binder bars, latch means detachably retaining said sheet engaging posts, binder and transfer bars in sheet binding position, a flexible binding having spaced portions secured to said binder bars for holding them in assembled relation, said binding having a portion adjacent one of said binder bars secured to said attaching bar for hingedly mounting said sheet binding unit on said attaching bar for movement relative to said back member, a keeper mounted on said back member, and a latch plate slidably mounted on said transfer bar in aligned relation for cooperation with said keeper in one position of said sheet binding unit for latching said unit to said back member and retain it against relative movement.

6. A loose leaf binder comprising a back member, cover members secured to opposite sides of said back member, a mounting bar attached to said back member having attaching posts, an attaching bar removably engaged on said attaching posts, latch means for detachably locking said attaching bar on said attaching posts and mounting bar, a sheet binding unit having a pair of binder bars to engage opposite sides of a sheet body, a transfer bar detachably associated with said binder bars at one side of a sheet body, cooperating sheet engaging posts mounted on said binder and transfer bars for retaining a sheet body between said binder bars, latch means detachably retaining said sheet engaging posts, binder and transfer bars in sheet binding position, a flexible binding having spaced portions secured to said binder bars for holding them in assembled relation, said binding having a portion adjacent one of said binder bars secured to said attaching bar for hingedly mounting said sheet binding unit on said attaching bar for movement relative to said back member, a keeper mounted on said back, a latch plate slidably mounted on said sheet binding unit adjacent said binder bar opposite the one secured adjacent to said attaching bar, said latch plate being aligned with and adapted to engage said keeper in one position thereof for retaining said sheet binding unit attached to said back member against relative movement.

CHARLES V. ST. LOUIS.
